UNITED STATES PATENT OFFICE.

HORACE J. RICHARDS, OF WATERVLIET, NEW YORK.

WINDOW-SHADE SUPPORTER.

1,338,591.

Specification of Letters Patent. Patented Apr. 27, 1920.

Application filed January 30, 1920. Serial No. 355,241.

To all whom it may concern:

Be it known that I, HORACE J. RICHARDS, a citizen of the United States, residing at Watervliet, in the county of Albany and 5 State of New York, have invented new and useful Improvements in Window-Shade Supporters, of which the following is a specification.

The object of my present invention is the 10 provision of an improved window shade supporter embodying such a construction that the shade-roller brackets may be adjustably and safely fixed at various distances from the top of a window casing according to the 15 amount of space for the passage of air that it is desired to allow for ventilating purposes between the shade roller and the top of the window casing.

To the attainment of the foregoing, the 20 invention consists in the improvement as hereinafter described and definitely claimed.

In the accompanying drawings, hereby made a part hereof:

Figure 1 is a front elevation of a window 25 equipped with my improvement.

Fig. 2 is a transverse section taken in the plane indicated by the line 2—2 of Fig. 1.

Fig. 3 is an enlarged vertical section taken through one of the upright bars of the shade 30 supporter and illustrating the manner in which the shade bracket is interlocked with and supported by said bar.

Similar numerals of reference designate 35 corresponding parts in all of the views of the drawings.

The window casing 1, and the shade roller 2 may be and preferably are of the ordinary well known construction.

My improvement comprises two upright 40 bars 3 and shade brackets 4, one to each bar 3. The bars 3 are identical in construction, and therefore a detailed description of the one shown in Fig. 3 will suffice to impart a definite understanding of both. Said bar

45 3 is preferably formed of metal, and comprises upper and lower portions 5 and 6 in which are apertures 7 for the passage of attaching screws, and a body portion 8, flanged at 8^a and 8^b, and having spaced 50 transverse portions 9, the said transverse

portions 9 separated by slots or openings 9^a. The portions 5 of the bars 3 are affixed to the inner sides of the upper portions of the side stiles of the casing 1. It is preferred in practice to make each of the bars 3 in 55 one piece of metal, but they may be made of any other material compatible with their purpose without involving departure from the scope of my claimed invention.

Each of the shade brackets 4 comprises 60 a body and an arm 10, preferably integral with the body and adapted to receive either the trunnion or the spring shaft section at the adjacent end of the shade roller 2. The body of each bracket 4 is preferably of 65 sheet-metal and is bent into loop form so as to afford a resilient tongue 11. The body of the bracket is extended below the arm 10 so as to form a pendent resilient tongue 12.

In the practical use of the improvement 70 each bracket is made to straddle one of the transverse portions 9 of its respective bar 3, so that the tongue 12 will rest at the inner side of the next lower transverse portion 9, and so that the tongue 11 will yieldingly 75 bear against and be frictionally engaged with the inner side of the body of the bar 3. This relative arrangement will tend to prevent casual upward movement of the bracket, and it will also be noticed that the 80 straddling of the bracket over one transverse portion 9 and the arrangement of the tongue 12 at the inner side of the next lower transverse portion 9 may be depended upon to effectively prevent accidental lateral disconnection of the bracket from its bar. When, however, it is desired to disconnect a bracket 85 4 from its bar 3, the same may be readily accomplished by simply moving the bracket upwardly relatively to the bar and so as 90 to disengage the looped portion of the bracket from one transverse portion 9 and the tongue 12 of the bracket from a lower transverse portion 9.

It will be manifest from the foregoing 95 that by reason of each of the bars 3 having a considerable number of transverse portions 9, the brackets 4 may be locked at various distances below the top of the window casing according to the space it is 100

desired to have between the shade roller and the top of the casing.

Having described my invention, what I claim and desire to secure by Letters-Patent, is:

In a supporter, the combination with a bar having spaced transverse portions; of a bracket having a body including an upper

resilient loop and a pendent resilient tongue, and an arm extending from the body; the upper loop removably straddling one transverse portion of the bar and the pendent tongue resting at the inner side of the next lower transverse portion of the bar.

In testimony whereof I affix my signature.

HORACE J. RICHARDS.
